HENRY JEPSEN, OF WEST HARTFORD, CONNECTICUT, ASSIGNOR TO JEWELL BELTING COMPANY, OF HARTFORD, CONNECTICUT, A CORPORATION OF CONNECTICUT.

MANUFACTURE OF RECEPTACLES.

Application filed September 19, 1925. Serial No. 57,291.

This invention relates to the manufacture of boxes, cases and other receptacles of leather or similar material. When cases are constructed of several pieces of leather in order to ensure maximum strength and attractive appearance the abutting edges of the adjacent walls are usually secured together by stitching. If the leather or other material from which the receptacle is to be built is heavy and thick, in making high class cases it has been customary to stitch the corners by hand which is a somewhat slow and costly operation particularly if the holes are first punched through the corners and then the thread passed through the holes and drawn tight by hand.

The object of the present invention is to provide a method of securing together the abutting edges of the article to be formed in a manner which retains the attractiveness and strength of stitched joints, but which is much quicker and cheaper to execute, as there are more simple machine operations, and yet produces joints that are fully as strong if not stronger than if stitched by hand in the old way.

This object is attained by stitching on a machine, with thread of suitable strength, the edge of one piece which is to be joined with the edge of another piece. The loops of this stitching are drawn tightly against or into the surface of the leather on the outside, while on the inside the stitch loops are left loose. The inside loops are then drawn so as to stand out from the inner surface of the stitched piece. The piece to be attached to the stitched piece is made up of a plurality of plies, the outside and inside layers being of leather or other material, with an intermediate sheet of solidified adhesive or cementing substance which is preferably waterproof. The intermediate cementing sheet is then subjected to the action of a solvent which reduces it or its surfaces to an adhesive condition, and the edges of this composite piece engaged with the open stitch loops on the inside of the other piece, one layer being on the inside and the other on the outside of the stitch loops. With the parts thus assembled they are pressed together until the adhesive solvent permeates the pores of the leather or other material and solidifies so as to strongly cement the pieces together and embed the stitching securely between the plies that are thus

joined together. By this method the joined edges of the pieces are practically stitched together and should one loop of the stitching become broken the other loops cannot unravel or draw out as they are completely embedded in the adhesive between the tightly cemented pieces.

The article shown for the purpose of illustrating the practice of this invention is made of substantial leather and is designed for containing a small camera. Such a case will be described, although it is to be understood that the invention is not limited to the special shape or size of the article nor the particular material from which it is made, or the use to which it is to be put, as many modifications in form may be produced by employing the method set forth.

In the accompanying drawings Fig. 1 shows a front elevation of a finished casing. Fig. 2 shows a side elevation. Fig. 3 is a view of the inside of a portion of the stitched piece which in this instance is to form the front, bottom, back, top and flap of the case. Fig. 4 is an edge view of the stitched piece with the stitches drawn out from the inside. Fig. 5 is a view of one of the side pieces. Fig. 6 is an edge view of the side piece with the layers separated to indicate its construction. Fig. 7 is a view on larger scale with a portion in section showing the manner in which the stitches pass through one piece and are embedded between the other pieces.

In making the case illustrated according to this invention a strip of leather of sufficient length to form the front 1, bottom 2, back 3, top 4 and flap 5 which is designed to be fastened down to the front by a snap 6, is, in a flat condition, run through a common commercial sewing machine and provided for a suitable distance on both edges with stitching 7 of thread having the required strength. (Fig. 3.) These stitches on the outside are drawn tightly against or into the outer surface of the leather. On the inside the stitches may be made over any suitable core which when removed leaves the loops loose on the inside. The ends 8 of the threads are pulled so as to draw the stitched end of the strip into U-shape, thus forming the front, bottom and back of the case, and tied so as to hold the leather in this shape. Fastening the thread ends together in this way also draws the loops out from the inner surface of the leather as illustrated in Fig. 4.

The sides 9 of the case are cut from leather or other material to a shape that will fit the edges of the bent stitched section of the other piece. (Fig. 5.) Each side is composed of two layers 10 of leather with an intermediate layer of sheet cementing material 11, which cementing layer may be if desired, sheet celluloid. In practice the upper ends of these layers of the sides are usually stuck together, leaving the lower ends separated as illustrated in Fig. 6. The free section of the intermediate cementing layer is then treated with a solvent, preferably by dipping it into a vessel containing a suitable liquid, which if the adhesive sheet is celluloid may be a solution of acetone. This is done without wetting the outer leather layers. This side piece with the surfaces of the cementing sheet coated with solvent or in a partially dissolved condition, is then thrust into the U-shaped section of the stitched piece until the edges of the composite side fit closely to the edges of the stitched piece and the stitch loops are between the inner and outer layers of leather of the side piece. With parts assembled in this manner the article is placed in a suitable form or press and held in shape while the adhesive permeates the fibers of the leather and becomes set. This not only provides stiff waterproof sides, but firmly embeds the stitched threads in the waterproof adhesive between the securely united layers of the sides.

As a result of this construction the pieces of leather comprising the article are fastened together in a manner that simulates the usual stitching, and practically as strong and durable as if the parts were fastened together in the old way by hand stitching, which improved method of making the cases is much cheaper than the old. With the sides made up of two pieces of leather it is possible to slit the outer layer before it is united with the inner to provide loops 12 for the passage of carrying straps. This leaves the inside of the case smooth and avoids the necessity of riveting or otherwise attaching loops to the sides for the carrying strap.

The invention claimed is:

1. The method of forming receptacles of pieces of leather or the like, which consists in providing the edge of one of the pieces to be secured with stitching, the loops of which are drawn tight against the outer surface of the piece and drawn away from the inner surface of the piece, forming the other piece of outer and inner plies with an intermediate ply of sheet cementing material, treating the cementing ply with solvent, fitting the edge of the composite piece to the edge of the stitched piece with a ply inside and a ply outside of the stitch loops, and holding the plies in this relation until

the cementing material intermediate the plies has become set.

2. The method of forming receptacles of pieces of leather or the like, which consists in providing the edge of one of the pieces to be secured with stitching, the loops of which are drawn tight against the outer surface of the piece and drawn away from the inner surface of the piece, applying the edge of another piece to the first mentioned piece inside of the stitch loops, applying the edge of a similar piece to the first mentioned piece outside of the stitch loops, and cementing said pieces together with the stitch loops between their edges.

3. The method of forming receptacles of pieces of leather or the like, which consists in providing the edge of one of the pieces to be secured with stitching, the loops of which are drawn tight against the outer surface of the piece and drawn away from the inner surface of the piece, separating the edge of the piece to be secured thereto and applying one separated section to the inside and one separated section to the outside of the stitch loops, and cementing said separated sections together with the stitch loops between.

4. The method of forming receptacles of pieces of leather or the like, which consists in providing the edge of one of the pieces to be secured with stitching, the loops of which are drawn tight against the outer surface of the piece and drawn away from the inner surface of the piece, fitting the edge of a composite piece to the stitched piece with a ply of the composite piece inside and a ply of the composite piece outside of the stitch loops, and cementing the plies of the composite piece together.

5. The method of forming receptacles of pieces of leather or the like, which consists in providing the edge of one of the pieces to be secured with stitching, the loops of which are drawn tight against the outer surface of the piece and drawn away from the inner surface of the piece, forming the other piece of plies with an intermediate ply of sheet solidified adhesive material, coating the sheet of adhesive material with a liquid solvent, and fitting the composite piece to the stitched piece with a ply inside and a ply outside of the stitch loops, and retaining the pieces thus assembled until the dissolved adhesive has become set.

6. The method of forming receptacles of pieces of leather or the like, which consists in providing the edge of one of the pieces to be secured with stitching, the loops of which on the inside are drawn away from the surface of the piece, forming the other piece of outer and inner plies with an intermediate ply of cementing material, fitting the edge of the composite piece to the edge of the stitched piece with a ply inside and a ply

outside of the stitch loops, and holding the plies together until the cementing material has firmly united them with the stitch loops between.

- 5 7. As a new article of manufacture, a receptacle formed of leather or the like, having a stitched wall and a composite wall fitted thereto, the plies of the composite wall being cemented together with loops of the
- 10 stitching cement between the edges of the composite wall.

8. As a new article of manufacture a receptacle formed of leather or the like having a stitched wall, the stitching loops extending through said wall and being tight on one side and loose on the other side, and a composite wall fitted thereto, the plies of the composite wall being cemented together with the loose loops of the stitching cemented between the plies. 15
